UNITED STATES PATENT OFFICE

OSCAR E. J. ABRAHAMSON, OF BUFFALO, NEW YORK, ASSIGNOR TO AMERICAN RADIATOR COMPANY, OF NEW YORK, N. Y., A CORPORATION OF NEW JERSEY

TESTING DEVICE

Application filed July 18, 1928. Serial No. 293,643.

My invention relates to new and useful improvements in testing devices, and more particularly to a device for use in testing the hardness of a body of sand or the like.

6 An object of my invention is to provide a device by means of which the hardness of a body of sand may be determined readily and with facility.

10 Another object is to provide a device which is simple, compact and efficient in operation.

The invention consists in the improved construction and combination of parts, to be more fully described hereinafter, and the novelty of which will be particularly pointed 15 out and distinctly claimed.

In the accompanying drawing, to be taken as a part of this specification, I have fully and clearly illustrated a preferred embodiment of my invention, in which drawing—

20 Figure 1 is a top plan view of the testing device embodying my invention, and

Fig. 2 is a vertical central section thereof on the line 2—2 of Fig. 1, but with certain of the parts in elevation.

25 Referring to the drawing by characters of reference, 1 designates a hollow tubular casing which is preferably cylindrical and comprises guide means. Within the casing 1 is a member 2 comprising a weight member 3 of

30 metal, preferably brass, and weighing substantially half a pound, and a penetration member 4 also of metal and preferably tool steel. In the lower end or bottom face 5 of member 3 is an axial internally threaded

35 recess 6. The member 4 has a surrounding flange 7 intermediate its ends and above which it is threaded for engagement with the internal threads of recess 6. Below the flange 7 the member 4 has a downward tapered conical point 8, the angle of the point preferably being substantially $22\frac{1}{2}$ °. The lower end of the casing 1 is externally threaded

40 to receive a cap member 9 which serves as a supporting element and which is provided with a central aperture 10 in the axial line of member 2, such that member 4 may project therethrough. The inside face 11 of the member 9 serves as a stop means to limit downward movement of the member 2. Within

45 the casing 1 above the member 2 is a cylind-

rical sleeve 12 of an external diameter substantially equal to the internal diameter of the casing 1. The sleeve 12 terminates at its upper end short of the top of the casing, as at 13, to provide a shoulder for a purpose to 55 be described. The lower end 14 of the sleeve 12 terminates at a height above the bottom face of the element 9 substantially equal to the length of members 3 and 4 to serve as a stop means, such that when the top face 15 of member 3 is in engagement with the lower end 14 of the sleeve, the tip 16 of the penetration member 4 will be in the plane of or flush with the under face 17 of member or element 9. The member 4 may be provided 60 with guide pins 18 adjacent its upper and lower ends to ride on the inside face of casing 1 to aid in maintaining the member 2 centrally or axially positioned in the casing 1. Through the side wall of the casing 1 is 70 a longitudinal slot 19, into or through which projects a pin 20 which extends transversely from the member 3 and which is rigid therewith. On the outside face of casing 1 is a catch member 21 which is secured rigidly in 75 position by rivets or the like 22, which also serve to hold the sleeve 12 in position within the casing. The catch member 21 includes a resilient arm 23 which terminates in a hook 24 which overlies the slot 19 and engages 80 and lies beneath the pin 20 when the member 2 is in retracted position with the top face 15 of member 3 in engagement with sleeve 12. The hook 24 normally lies in the path of movement of the pin 20 and is provided with a cam face 25, so that on movement of the member 2 to retracted position, the pin 20 will flex the catch member out of its path and permit the catch member to snap beneath it into locking or holding position. The catch member 21 is provided 85 with parallel lugs 26 adjacent the rivets 22 between which extends a pivot pin 27. Journaled on the pin 27 between lugs 26 and at substantially its midpoint, is a lever member 28. The lower end of the member 28 is secured to the resilient arm 23 adjacent hook 24 by a rivet or the like 29. The other end 28a of the lever extends upwardly from the lugs 26 and provides a hand grip for flexing 90

95

100

the arm 23 to release the member 2. Axially of the member 3 in the top face 15 thereof, is a recess 30, in which is secured, by a cross-pin 31 or the like, the lower end of a cylindrical member 32 having a surrounding flange 33 seating on the face 15. Above the flange 33 the member 32 is hollow, as at 34, to form a sleeve having a helical slot 35. Overlying the top end of the casing 1 is a dial plate member 36, preferably circular, which seats on the shoulder 13 and has a surrounding flange 37 which overlies and seats on the end of the casing 1. The plate member 36 has indicia 38 marking off the circumference of the plate member 36 into thirty-two equal parts, each division on the dial indicating one sixty-fourth of an inch of movement of the member 2. Above the dial plate member 36 is a pointer 39, which is mounted rigidly on one end of a shaft 40 which projects through a central bearing aperture 41 in the member 36. On the shaft 40 between the pointer and the member 36, is a bearing or spacer washer 42, and also on the shaft is a flange 43 which engages the under face of member 36. The shaft 40 depends into the cylindrical bore 34 of member 32 and is provided with a cylindrical head 44 from which projects a pin 45 which runs in the slot 35. On the plate member 36 is an annulus 46 which supports a glass cover-plate 47. The member 36, annulus 46 and plate 47 are clamped in position on the casing 1 by a sleeve 48 which is threaded on the casing 1, as at 49, and has an inwardly extending flange 50 which overlies the plate 47.

The operation of my device is as follows: The device is particularly adapted for determining the hardness of molding sand, but it is evident that it may also be used in determining the hardness of other finely divided bonded material. The member 2 is raised to its retracted position, as shown in Fig. 2, which will set the dial pointer 39 in the position of Fig. 1 and at zero. The device is then placed upon a body of molding sand of which it is desired to determine the hardness, with the lower face 17 of element 9 supporting the device and being flush with the top face of the sand. The lever 28 is now operated to release pin 20, permitting the weighted member 2 to descend by force of gravity and press the pointed penetration member 4 into the sand. As the weighted member 2 presses the point 16 into the test material, the pin 45 will ride in the spiral groove 35, thus causing rotation of the shaft 40 and the pointer 39 which will indicate on the scale or dial 38 the number of sixty-fourths of an inch which the tip 16 of point 8 of member 4 has moved into the sand, or the extent of movement of the member 2. The number of sixty-fourths of an inch which the half pound weight member 2 pushes the point 16 into the mold ma-

terial will indicate the hardness thereof, or how tightly it is packed. It is apparent that I have thus provided a device by which the relative hardness of molding sands may be readily determined, and by which it may be ascertained if a molding sand of the requisite hardness for the desired molding operation has been provided.

What I claim and desire to secure by Letters Patent of the United States is:

1. In a device of the character described, a tubular guide means, a weighted member reciprocable within said means and having a penetration member at its lower end, said weighted member being movable within said guide means by force of gravity and being adapted to occupy a retracted position, means closing the upper end of said guide means, and means carried by said closing means and cooperable with said weighted member to indicate the extent of movement of said weighted member under force of gravity from said retracted position.

2. In a device of the character described, a tubular casing comprising guide means, a weighted member reciprocable in said casing, said member falling freely under the force of gravity upon its release, a penetration member carried by said weighted member and projecting from the lower end of said casing when said weighted member moves under the force of gravity, said weighted member being adapted to occupy a retracted position in said casing, means to hold said weighted member releasably in retracted position against the force of gravity, means closing the upper end of said casing and having indicia, and means actuated by said weighted member and cooperable with said indicia to indicate the extent of free falling movement of said penetration member from said casing under the force of gravity upon release of said holding means.

3. In a device of the character described, a tubular casing comprising guide means, a weighted member reciprocable in said casing, said member falling freely under the force of gravity upon its release, said weighted member being adapted to occupy a retracted position in said casing and having a penetration member at its lower end, means to hold said member releasably in retracted position against the force of gravity, a dial plate closing the upper end of said casing and having indicia thereon, a pointer cooperable with said indicia to indicate the extent of free falling movement of said weighted member from retracted position under the force of gravity, and means operatively connecting said pointer and said weighted member.

4. In a device of the character described, a weighted member having a penetration member at its lower end, means to guide said weighted member for free vertical movement under the force of gravity, said member being

adapted to occupy a retracted position, a plate member supported on said guide means and carrying indicia, a pointer having a shaft and mounted on said plate member for oscillation and cooperable with said indicia, said shaft having a transverse pin, and a cylindrical member carried by said weighted member and projecting upwardly therefrom and having a helical slot, said pin projecting into said slot whereby movement of said weighted member under the force of gravity will cause rotation of said shaft to move said pointer to indicate the extent of movement of said weighted member from retracted position.

5 5. In a device of the character described, a weighted member having a penetration member at its lower end, means to guide said weighted member for free vertical movement under the force of gravity, said member being adapted to occupy a retracted position, a plate member supported on said guide means and carrying indicia, a pointer having a vertical depending shaft and mounted on said plate member for oscillation and cooperable with said indicia, said shaft having a transverse pin, and a sleeve carried by said weighted member and projecting upwardly therefrom around said shaft and having a helical slot, said pin projecting into said slot whereby movement of said weighted member under the force of gravity will cause rotation of said shaft to move said pointer to indicate the extent of movement of said weighted member from retracted position.

10 20 25 30 35

In testimony whereof I have hereunto signed my name.

OSCAR E. J. ABRAHAMSON.
